CLAIM

The ornamental design for a phone case, as shown and described.

DESCRIPTION

FIG. 1 is a perspective view including a front, top and one side of the phone case;

FIG. 2 is a perspective view including a front, top and an opposite side of the phone case;

FIG. 3 is a perspective view including a rear, bottom and an opposite side of the phone case;

FIG. 4 is a perspective view including a rear, bottom and one side of the phone case;

FIG. 5 is an elevational view of the front of the phone case of FIG. 1;

FIG. 6 is an elevational view of the rear of the phone case of FIG. 1;

FIG. 7 is an elevational view of the opposite side of the phone case of FIG. 1;

FIG. 8 is an elevational view of the side of the phone case of FIG. 1;

FIG. 9 is a plan view of the top of the phone case of FIG. 1; and,

FIG. 10 is a plan view of the bottom of the phone case of FIG. 1.

The dot-dash broken line in FIGS. 1-2 and 5 represents the bounds of the claimed design. The dot-dash broken line and unshaded region bounded by the dot-dash broken lines forms no part of the claimed design.

1 Claim, 8 Drawing Sheets
